His Attorney.

UNITED STATES PATENT OFFICE

2,385,634

BASE FOR ELECTRIC LAMPS OR SIMILAR DEVICES

John J. Malloy, Cleveland Heights, Ohio, assignor to General Electric Company, a corporation of New York

Application July 21, 1943, Serial No. 495,790

5 Claims. (Cl. 176—32)

My invention relates to electric incandescent lamps and similar devices comprising a bulb having an electrical energy translation element or filament sealed therein and a base on said bulb. More particularly, my invention relates to a base structure for such devices.

One of the most common forms of base construction in use at present on electric incandescent lamps comprises a threaded metal shell, usually of brass, having a glass insulator button fastened to one end thereof and a metal end contact or eyelet (likewise usually of brass) secured to the said button and insulated thereby from the metal shell. Inasmuch as the base of a lamp is usually discarded along with the other parts thereof upon burn-out of, or other damage to the lamp, the metal of the base shell and eyelet is accordingly wasted upon discarding the lamp.

One object of my invention is to provide a screw-thread base arrangement for electric incandescent lamps and similar devices which is simple and economical in construction and which utilizes a minimum amount of metal.

A feature of the invention is the use of a metal strip or band which is spun or wound into the form of a screw-thread on the neck of the bulb or on a cup-shaped glass body attached to the bulb neck, the bulb neck or the glass body preferably being provided with a screw-thread molded on the cylindrical exterior surface thereof and over which the metal strip is spun or wound to form a screw-thread side contact for the lamp.

Further objects and advantages of my invention will appear from the following description of species thereof and from the accompanying drawing in which:

Fig. 1 is a partial longitudinal sectional view, on an enlarged scale, of a portion of an electric incandescent lamp provided with a base structure comprising my invention; Fig. 2 is an elevation of the portion of the lamp shown in Fig. 1; Fig. 3 is a transverse sectional view taken on the line 3—3 of Fig. 1; Fig. 4 is a transverse section taken on the line 4—4 of Fig. 1; Fig. 5 is a perspective detail view of the metal screw-thread conductor element of the base shown in Figs. 1—4; Fig. 6 is a longitudinal section on the line 6—6 of Fig. 7 of a modified form of base construction comprising my invention; and Fig. 7 is a transverse section on the line 7—7 of Fig. 6.

Referring to Fig. 1, the lamp there shown comprises a glass bulb 10 provided with a cylindrical neck portion 11, the said neck portion being of reduced diameter so as to form a shoulder 12 on the bulb. Sealed within the bulb 10 is a conventional filament mount structure comprising a re-entrant stem 13, an exhaust tube 14, a pair of lead-in wires 15, 16, and an electric

energy translation element or filament (not shown) connected to the inner ends of the lead-in wires 15, 16 and sealed with the bulb 10.

Secured to the neck 11 of the bulb is a base structure 17 according to the invention. The said base comprises a molded cup-shaped body 18 of insulating material, such as glass, having a cylindrical side wall portion 19 and a button-shaped end wall portion 20. The side wall 19 of the glass body 18 is so shaped as to fit snugly around the neck 11 of the bulb with the rim 21 of the side wall 19 abutting or fitting against the shoulder 12 on the bulb.

The base 17 may be secured to the neck 11 of the bulb by means of a plurality of locking keys or pins 22 which extend through apertures 23 in the cylindrical side wall 19 of the glass body 18 and are formed with internal heads 24 which fit into corresponding shallow dish-shaped depressions 25 in the neck 11 of the bulb. Two of such locking keys 22 are preferably employed, the said keys being located at diametrically opposite points on the glass body 18. The keys 22 are made of a readily fusible metal such as solder, and are formed by inserting the solder under pressure, while in a molten state, into the apertures 23 in the glass body 18 so as to flow into and completely fill the said apertures as well as the shallow depressions 25 in the bulb neck 11.

The cylindrical side wall portion 19 of the glass body 18 is provided with an external screw-thread formed in part by conductor means in the form of a narrow metal strip or band 26, of brass or other suitable non-corrosive metal, which is disposed in a helix on the outer surface 27 of the cylindrical wall 19 of the glass body 18. As shown in Fig. 1, the metal strip 26 is of arcuate cross-section to form the top or convex portions of the screw-threads. The valley or trough portions of the screw-thread is formed by the outer surface 27 of the cylindrical wall 19 itself. The helical metal strip 26 is of sufficient length to form at least one, and preferably one and one-half complete threads.

To lock the helical metal strip 26 against rotation on the cylindrical wall 19, the opposite ends of the strip are suitably secured or anchored to the said wall. For this purpose, the metal strip 26 is provided with inwardly bent tongues 28, 29 at its opposite ends, which tongues extend through suitable apertures in the wall 19 and are bent back around the inner surface 30 of the said wall, as indicated at 31 in Figs. 3 and 4. Preferably, the tongue 28 at that end of the metal strip 26 nearest the rim 21 of the glass body 18 extends through one of the apertures 23 for the solder keys 22 and is firmly held in place in the said aperture by the solder key therein, while the tongue 29 at the other end of the metal strip 26

extends through a slit-shaped aperture 32 (Fig. 2) in the wall 19 of the glass body.

To provide a firm support for the metal strip 26 and prevent displacement thereof longitudinally of the cylindrical wall 19, suitable protuberant positioning and support means are provided, preferably in the form of a continuous helical ridge or screw-thread 33 molded on the outer surface 27 of the said wall 19 and over which the said strip fits tightly. The fixation of the opposite ends of the metal strip 26 to the glass body 18 by the tongues 28, 29 holds the strip in place against rotation on the helical positioning ridge 33. Instead of employing a ridge 33 of continuous form, the positioning means for the metal strip 26 may be constituted by a plurality of spaced protuberances disposed in helical formation around the cylindrical wall 19 of the glass body 18. The metal strip 26 may be applied to the molded screw-thread 33 either by spinning or wrapping it therearound, or by preforming it into screw-thread shape and then slipping it over the end of the bulb neck into place on the molded screw-thread 33.

The metal strip 26, in addition to serving as a screw-thread for securing the lamp in a socket, also serves as the side contact for the lamp. For this purpose, one lead-in wire 15 of the lamp is suitably connected to the metal strip 26, preferably by embedding the said lead-in wire in that solder key 22 which contacts the tongue 28 of the metal strip 26. The other lead-in wire 16 is connected to a suitable bottom or center contact 34 preferably in the form of a small button of solder disposed in a recess 35 in the outer surface of the button-shaped end wall 20 of the glass body 18. The said lead-in wire 16 extends through an aperture 36 in the said end wall 20 of the glass body and is embedded in the solder contact 34.

The modification shown in Figs. 6-7 differs from the previous form of the invention in that the glass body 18 is eliminated and the helical metal strip or band 37 mounted instead directly on the bulb neck 11 which, for such purpose, may be provided with a molded screw-thread 38 over which the metal strip 37 is applied, as before. The said strip 37 is secured against rotation on the molded screw-thread 38 by bending its opposite ends inwardly and back upon themselves to form tongues 39, 40 which extend into and are locked within undercut depressions or recesses 41, 42 in the cylindrical wall of the bulb neck 11. Leading-in wire 15 is suitably connected to the metal strip 37, preferably to that end of the strip nearest the end of the bulb neck 11. For this purpose, the end wall of the bulb may be formed with an outer groove or channel 43 which extends to the recess 42 and through which the lead-in wire 15 extends into the recess 42 where it is suitably secured, as by soldering, to the tongue 40 of the metal strip 37. The other leading-in wire 16 is connected to a suitable bottom or end contact 44 on an insulating (preferably glass) button 45 cemented or otherwise attached to the end of the bulb neck. As shown, the end contact 44 may be in the form of a metal eyelet 46 fastened to the insulator button 45 and to which the leading-in wire 16 is soldered.

While I have shown and described the preferred forms of my invention, it is obvious that other modifications are possible within the scope

thereof. Thus, instead of mechanically attaching the base 17 (Figs. 1-5) to the bulb neck 11 by means of the solder keys 22, it may be secured to the bulb neck by conventional basing cement.

What I claim as new and desire to secure by Letters Patent of the United States is:

1. An electrical device comprising a bulb having a neck portion and a base mounted on said neck portion and comprising a molded body of insulating material having a cylindrical wall portion surrounding the bulb neck, said bulb neck having a plurality of depressions therein and the cylindrical base wall having a plurality of openings opposite said depressions, a plurality of locking keys of easily fusible metal filling the said depressions and openings in said bulb neck and base wall to secure the base to the bulb neck, conductor means wound around and secured to the said wall portion and arranged to define a helix for engagement with the screw-threads of a socket, one end of said conductor means being embedded and anchored in one of said locking keys, and a leading-in wire embedded in the said one locking key and electrically connected thereby to the said conductor means.
2. An electric lamp base comprising a cylindrical wall portion of insulating material with a helical screw thread of at least one full turn formed on its outer surface, and contact means consisting of a helically formed narrow metal band of at least one full turn conforming to the pitch of said screw thread and wrapped around the surface thereof, said band having inwardly bent ends anchored in cavities in said wall portion.
3. An electric lamp base comprising a cylindrical wall portion of insulating material with a helical screw thread of at least one full turn formed on its outer surface, and contact means consisting of a helically formed narrow metal band of at least one full turn conforming to the pitch of said screw thread and being curved in cross-section in conformity with the crest of said screw thread, said band being wrapped around the crest of said screw thread and having inwardly bent ends anchored in cavities in said wall portion.
4. An electric lamp base comprising a cylindrical wall portion of insulating material with a helical screw thread of approximately one and a half turns formed on its outer surface, and contact means consisting of a helically formed narrow metal band of approximately one and a half turns conforming to the pitch of said screw thread and wrapped around the surface thereof, said band having inwardly bent ends anchored in cavities in said wall portion.
5. An electric lamp comprising a sealed bulb having lead-in wires extending therefrom, and a base portion of insulating material having a helical screw thread of at least one full turn formed on its outer surface, and contact means consisting of a helically formed narrow metal band of at least one full turn conforming to the pitch of said screw thread and wrapped around the surface thereof, said band having inwardly bent ends anchored in cavities in said base portion, one of said lead-in wires extending into one of said cavities and being soldered therein to an end of said band.

JOHN J. MALLOY.
